RAIL FLAW DETECTOR MECHANISM

George L. Jones, Garden City, Harcourt C. Drake, Hempstead, and Henry Schumacher, Brooklyn, N. Y., assignors to Sperry Products, Inc., Brooklyn, N. Y., a corporation of New York

Application February 5, 1935, Serial No. 5,046

12 Claims. (Cl. 177—311)

This invention relates to rail flaw detector mechanisms of the type embodied in the Sperry rail flaw detector. The operation of these mechanisms is now well known and consists of a car which operates along the rails and carries a mechanism responsive to internal flaws. When such a flaw is encountered an indication is made upon a chart in the moving car and at the same time marking means such as paint is discharged 10 on the rail in the region of flaw.

It is highly desirable that the marking means should operate quickly in response to energization in order that the mark on the rail may be properly located, and it is further desirable that the 15 mark be limited in extent to substantially the region of a flaw. If the marking means is slow in responding to an impulse it may be that the paint will be placed upon the rail at a point several inches removed from an actual flaw and 20 may be located at a surface defect such as a burn which the operator will misinterpret. Also, if the mark is too long it may be that the said mark originally was made in response to a surface defect but extends along the rail to such a distance 25 that a fissure near a surface defect will be missed since the operator will interpret the mark, no matter how long, as being due to the surface defect.

This invention, therefore, has for its principal 30 object the provision of rail marking means and actuating means therefor which will result in a quick response of the marking means and which will yield a mark of relatively short length.

Further objects and advantages of this invention 35 will become apparent in the following detailed description thereof.

In the accompanying drawings,

Fig. 1 is a side view of a Sperry rail fissure detector car, the main portion of the car being 40 broken away to show the detector mechanism.

Figs. 2 to 5 inclusive are views largely in the form of wiring diagrams illustrating various forms of our invention.

Fig. 6 is a section taken substantially on the 45 line 6—6 of Fig. 5.

Referring to Fig. 1 of the drawings, there are shown the parts of a standard Sperry rail fissure detector car which includes a car-body 10 operating along the rails R. Fissure detection is accomplished by passing current through each rail from a generator G within the car-body supplying current to spaced current brushes 11 and 12 supported upon the current brush carriage 13 which when in lowered or effective position is 50 adapted to ride upon the rail by means such as

wheels 15. The current brush carriage 13 is normally held in elevated or ineffective position by means of springs, not shown, and cables 16, but when it is desired to lower said carriage, fluid pressure such as compressed air is supplied 5 to the cylinders 17 to force out pistons 18 which are pivotally connected at 19 to the current brush carriage 13. The current passed through the rail by way of spaced brushes 11 and 12 will establish an electromagnetic field surrounding the rail and 10 this field will be uniform except in the region of flaw, where it will be distorted. Such distortions of the electromagnetic field are detected by a flaw responsive mechanism which may take the form of a pair of opposed induction coils 22 supported 15 in a housing 23 at a constant distance above the rail surface by means of a carriage 24. Said carriage 24 is mounted on current brush carriage 13 by means of loosely fitting bolts 25 and springs 26 to permit said carriage 24 while riding on the 20 rail on means such as wheels 27 to move independently of carriage 13 so that the said carriage 24 may at all times maintain parallelism with the rail surface regardless of irregularities thereof. The coils 22 normally cut the same number, 25 of lines of force, but on entering a region of flaw, first one coil and then the other will cut a different number of lines of force to generate a differential E. M. F. which after being suitably amplified by an amplifier A may be caused to 30 actuate a pen P operating on a chart, now shown. At the same time that pen P is actuated, there is actuated also marking means which may take the form of a paint gun 30 mounted on the current brush carriage 13 a sufficient distance behind the flaw responsive members 22 to 35 compensate for the movement of the car and for the lag in operation of the paint gun.

As stated in the introduction hereto, it is highly desirable that the paint gun be so operated that a 40 relatively short mark will be placed upon the rail in the region of flaw, regardless of the magnitude of the impulse passing through the amplifier A or the length of time that said impulse persists. For this purpose we have provided various forms 45 of our invention. In all of these forms there is utilized a single principle, i. e., to actuate a member in response to an impulse from the amplifier, and to utilize only a fraction of the total movement of said member to operate the marking 50 means.

In the form of the invention shown in Fig. 2, the impulse from amplifier A energizes magnet 40 which attracts its armature 41 against the action of spring 42 to close a set of contacts 43 and close 55

- a circuit including a source of energy, such as battery B, to energize a magnet 44 which attracts an armature 45 against the action of a spring 46 to actuate the pen P on the chart, not shown.
- 5 The pen P normally draws a straight line on the chart which is moving continuously, but when actuated by the magnet 44 it makes a notch in the straight line, indicating the presence of a flaw in the rail.
- 10 At the same time that pen magnet 44 is energized to cause pen P to indicate on the chart that a flaw has been encountered, we cause the rail-marking means to be actuated for a constant predetermined degree each time an impulse passes
- 15 through amplifier A. For this purpose we employ a motor M which rotates a shaft 50 upon which there is fixed a valve 51 journaled within a bearing 52, said valve having an opening 53 diametrically therethrough so that once during each revolution thereof said opening 53 will connect the paint supply opening 54 with a discharge opening 55. The motor M is normally deenergized but is adapted to be energized when contacts 43 close. For this purpose the circuit through motor M extends through a contact 56 carried by contact arm 57 which engages a contact 58 carried by contact arm 59. The contact 56 is normally held out of engagement with contact 58 by reason of spring 60. When contacts 43 close, 20 however, there is energized a magnet 61 which is adapted to attract contact arm 57 as an armature and move contact 56 into engagement with contact 58 to close the circuit through the motor M.
- Upon an extension of shaft 50 there is carried a 25 detent wheel 62 having notches 63 adapted to contact with a detent 64 which is normally held by springs 65 pressed against the wheel 62 and will therefore engage in one or the other of notches 63 to prevent rotation of the motor M. To permit
- 30 motor M to rotate shaft 50 and therefore bring opening 53 into coincidence with the paint supply opening 54 and outlet 55 there is provided means for withdrawing detent 64 from the respective notches 63 before contact 56 engages contact 58.
- 35 For this purpose a spring contact arm 57 carries a lower contact 66 which engages a contact 67 carried by a spring contact 68 when the said arm 57 is in its unattracted position. When contacts 40 43 close, the circuit is completed by way of contacts 66, 67 and magnet 69 which then attracts its armature 70 to withdraw detent 64 from notch 63 to permit motor M to rotate shaft 50 when the said motor is energized. Contacts 66 and 67 remain closed as spring arm 57 is attracted
- 45 by magnet 61 and in the position indicated in dotted lines at S the contacts 66 and 67 are still closed by reason of the fact that in the full line position of arm 57 contact arm 68 is under tension and as arm 57 rises contact 67 follows in engagement with contact 66 by reason of the tension in spring arm 68 relaxing. In the dotted line position shown at S, therefore, contacts 66 and 67 engage, as well as contacts 56 and 58. Thus, magnet 69 at this moment holds detent 64 withdrawn from groove 63 while the motor is energized to rotate shaft 50. A slight further attraction of arm 57 to the dotted line position indicated at T breaks the contacts 66 and 67 to deenergize magnet 69 and permit armature 70 to drop, while
- 50 contacts 56 and 58 remain in engagement to energize motor M. The dropping of armature 70 does not cause detent 64 to drop into its groove 63 by reason of the fact that shaft 50 has rotated in the meantime to move groove 63 out of engagement with the detent 64. The said detent 64

therefore rides upon the outer surface of wheel 62 until the groove 63 on the opposite side of wheel 62 engages said detent 64 to stop the rotation of the motor. The opening 53 is positioned at an angle, preferably at right angles, to the line joining groove 63 so that in a half revolution of motor shaft 50 there is sure to be one full engagement of opening 53 with paint supply 54 and outlet 55. Since the motor rotates at the same speed every time it is actuated, the length of time that opening 53 engages supply opening 54 and discharge opening 55 will be constant and thus a paint mark of constant length will be obtained upon the rail. It will thus be seen that regardless of how long contacts 43 remain energized, and therefore motor M remains energized, only one-half revolution of shaft 50 will take place by reason of the detent and groove mechanism just described, and only a fraction of this movement is utilized to actuate the rail marking means.

In another form of the invention, shown in Fig. 3, the impulse from amplifier A energizes magnet 40 to break contacts 43 which are normally held closed by spring 42, so that pen magnet 44 is normally energized, and when an impulse from amplifier A comes through, said magnet will be deenergized to cause pen P to be released by the action of spring 46 to make a mark on the chart. At the same time, a transformer F sends an impulse through a polarized relay 72 to close a set of contacts 73 and energize a magnet 74 which attracts its armature 70' against the action of springs 65' to withdraw a detent 64' from a groove 63' formed in a wheel 62' to permit motor M which is continuously energized from any suitable source such as battery B' to rotate a shaft 50 upon which said wheel 62' is mounted. The momentary release of detent 64' from groove 63' permits the wheel 62' to be rotated sufficiently so that when the impulse through transformer F ceases the detent 64' drops on to the outer periphery of wheel 62' because the groove 63' has passed beyond said detent. The motor M may thus rotate freely until another groove 63' diametrically opposite the first 45 groove is encountered by the detent 64' and thus holds the motor against any further rotation until another impulse from amplifier A sends an impulse through the transformer F. In order that the paint gun shall be operated for a constant interval each time motor M is set free to run for half a revolution, we have provided on an extension of shaft 50, a wheel 75 provided with contact segments 76 of less than a semi-circle and positioned similarly to the position of groove 55 63' on wheel 62'. This means that for each half revolution of motor M one of the contact segments 76 will engage the contact brushes 77 to energize magnet 78 which will attract its armature 79 against the action of spring 80, said armature 79 forming the valve stem of a valve 81 controlling the emission of paint from paint supply 82 through outlet 83. Since each impulse through amplifier A results in a single impulse through transformer F and therefore a single release of detent 64' from its groove 63', only one-half revolution of motor M will take place for each impulse through amplifier A and therefore only one actuation of the paint gun will occur. Further, since the speed of motor M is the same at each actuation thereof, the time of energization of the paint gun will always be constant and therefore a paint mark of constant length will be obtained.

In the Fig. 4 form of the invention, parts simi-

lar to the Fig. 3 form are indicated by the same numerals. When the contacts 43 open in response to an impulse from amplifier A, the pen P is actuated and at the same time magnet 84 is deenergized to release its armature 85 by means of spring 86 which withdraws detent 87 in engagement with stop 88 formed on a lever 89. The release of detent 87 permits spring 90 to swing lever 89 to the right, in Fig. 4, and for a fraction 5 of the arc through which lever 89 swings there is caused to be energized a magnet 78' which attracts armature 79' against the action of spring 80', said armature 79' forming the valve stem of paint gun valve 81'. The upper end of lever 89 10 carries a contact 91 which engages contact 92 pivoted at 93. Said engagement takes place through a fraction of the arc described by lever 89 in passing from the full line to the dotted line position, the contact 91 eventually sweeping 15 past the contact 92 which is then returned to its original position by spring 94. When contacts 93 close once more magnet 84 is energized to close a set of contacts 97 which energize a magnet 98 whose armature is formed by the swing lever 89. 20 The strength of magnet 98 is such as to overcome spring 90 and draw the lever 89 back to its original position. On the return stroke, contact 91 does not make contact with contact 92 by reason 25 of the insulation strip 95 carried at the lower end of contact 92 and the bevelled surfaces of contacts 91 and 92. Thus, only during a fraction 30 of the movement of lever 89 toward the right, in Fig. 4 is contact made between contacts 91 and 92, and since the duration of engagement of said 35 contacts is constant for each actuation of lever 89, the paint gun valve 81' will be actuated for a constant length of time at each actuation thereof to yield a paint mark of constant length.

A different form of the invention, but embodying the same principles as the forms hereinbefore described, is disclosed in Figs. 5 and 6. In this form contacts 43 are normally open and are designed to be closed when an impulse passes through amplifier A to energize pen magnet 44 40 to actuate pen P on the chart. At the same time that magnet 44 is energized there is also energized a magnetic clutch 100 which normally rotates with shaft 101 of the motor M. The energization of said magnet causes it to attract a cam member 102 which has slight frictional engagement with the shaft 101 but is normally held against rotation therewith by means of spring 103 engaging a projection 104 on said cam member 102. Thus the cam member 102 rotates with shaft 101 until 45 projection 104 strikes spring member 105, whereupon it is held against any further rotation. When, however, magnet 100 is energized it attracts the member 102, causes clutch members 105 to engage so that member 102 is rotated together with shaft 101, overcoming the resistance of spring 103, and the said projection 104 rides under one end 106 of a lever 107 which engages 50 valve stem 108 of the paint gun valve 81. As said projection passes beneath the end 106 of lever 107 it will lift the valve to cause paint to be ejected, and since the speed of motor M is the same at each actuation thereof, the valve will always be lifted for the same interval to give a paint mark of constant length. The diameter of member 102 and the speed of motor M are such 55 that clutch 105 will be engaged for less than the one revolution thereof, the period of said one revolution being predetermined to exceed the longest impulse that may come through amplifier A in response to flaw. The release of clutch 105

permits spring 110 to return member 102 to its original position and leaves member 102 in slight frictional engagement with shaft 101 to be rotated therewith until projection 104 strikes spring 103 where it will be held against any further rotation 5 since spring 103 is of sufficient strength to overcome the frictional engagement of member 102 with the shaft 101.

In accordance with the provisions of the patent statutes, we have herein described the principle and operation of our invention, together with the apparatus which we now consider to represent the best embodiment thereof, but we desire to have it understood that the apparatus shown is only illustrative and that the invention 10 can be carried out by other equivalent means. Also, while it is designed to use the various features and elements in the combination and relations described, some of these may be altered and others omitted without interfering with the more 15 general results outlined, and the invention extends to such use.

Having described our invention, what we claim and desire to secure by Letters Patent is:

1. In a rail flaw detector mechanism, means 20 responsive to flaw adapted to generate continuous impulses of varying duration depending upon the size and type of flaw, rail marking means, operating means for said marking means comprising a motor, means whereby said impulses set said 25 motor in operation, means whereby continued operation of said motor is capable of actuating said marking means periodically, means for limiting the movement of said motor to a single actuation of said marking means in response to a flaw, 30 and means whereby said marking means is actuated by said motor during a predetermined portion of the movement thereof for a predetermined period in excess of the longest impulse duration.

2. In a rail flaw detector mechanism, means 40 responsive to flaw adapted to generate continuous impulses of varying duration depending upon the size and type of flaw, rail marking means, operating means for said marking means comprising a motor, means whereby said impulses 45 set said motor in operation, a rotary valve operated by said motor, a valve casing having an outlet, a supply of marking fluid connected to said casing, said valve having means for connecting said supply to said outlet for a predetermined portion of the movement of said valve in 50 said casing whereby continued operation of said motor would result in periodic actuation of said marking means, and means for limiting the movement of said motor to a single actuation 55 of said marking means in response to a flaw for a predetermined period in excess of the longest impulse duration.

3. In a rail flaw detector mechanism, means 60 responsive to flaw adapted to generate continuous impulses of varying duration depending upon the size and type of flaw, rail marking means, operating means for said marking means comprising a rotatable member, means whereby said 65 impulses rotate said member, means whereby said marking means is actuated by said member, said last-named member including an electric circuit, contacts in said circuit, means whereby said member actuates said contacts during a predetermined portion of the rotation of said member, 70 continued rotation of said member being capable of periodic actuation of said contacts, and means for limiting the movement of said member to a single actuation of said contacts in response to a flaw.

4. In a rail flaw detector mechanism, means responsive to flaw adapted to generate continuous impulses of varying duration depending upon the size and type of flaw, rail marking means, operating means for said marking means comprising a continuously operating motor, an operating member normally disconnected from said motor, a clutch for connecting said member to said motor, said clutch being normally ineffective and adapted to be rendered effective by said impulses for a predetermined period in excess of the longest impulse duration, and means whereby said marking means is actuated by said member.
5. In a rail flaw detector mechanism, means responsive to flaw adapted to generate continuous impulses of varying duration depending upon the size and type of flaw, rail marking means, operating means for said marking means comprising a continuously operating motor, an operating member normally disconnected from said motor, a clutch for connecting said member to said motor to rotate the member, said clutch being normally ineffective and adapted to be rendered effective by said impulses for a predetermined period in excess of the longest impulse duration, and means including a projection carried by said member whereby said marking means is actuated by said member for a predetermined portion of the movement of said member.
6. In a rail flaw detector mechanism, means responsive to flaw adapted to generate continuous impulses of varying duration depending upon the size and type of flaw, rail marking means, operating means for said marking means comprising a continuously operating motor, an operating member normally disconnected from said motor, an electric clutch for connecting said member to said motor to rotate the member, said clutch being normally ineffective and adapted to be rendered effective by said impulses for a predetermined period in excess of the longest impulse duration, and means including a projection carried by said member whereby said marking means is actuated by said member for a predetermined portion of the movement of said member.
7. In a rail flaw detector mechanism, means responsive to flaw adapted to generate continuous impulses of varying duration depending upon the size and type of flaw, rail marking means, operating means for said marking means comprising a movable member, means whereby said varying impulses move said member a predetermined, substantially constant distance at a substantially constant speed, and means whereby said marking means is actuated by said member during a portion of the movement thereof.
8. In a rail flaw detector mechanism, means responsive to flaw adapted to generate continuous impulses of varying duration depending upon the size and type of flaw, rail marking means, operating means for said marking means comprising a movable member, means whereby said varying impulses move said member a predetermined, substantially constant distance at a substantially constant speed, and means whereby said marking means is actuated by said mem-
- ber during a predetermined portion of the movement thereof.
9. In a rail flaw detector mechanism, means responsive to flaw adapted to generate continuous impulses of varying duration depending upon the size and type of flaw, rail marking means, operating means for said marking means comprising a movable member, means whereby said varying impulses move said member a predetermined, substantially constant distance at a substantially constant speed, means whereby continuous movement of said member is capable of actuating said marking means periodically, means for limiting the movement of said member to a single actuation of said marking means in response to a flaw, and means whereby said marking means is actuated by said member during a predetermined portion of the movement thereof.
10. In a rail flaw detector mechanism, means responsive to flaw adapted to generate continuous impulses of varying duration depending upon the size and type of flaw, rail marking means, operating means for said marking means comprising a movable member, means whereby said varying impulses move said member through a predetermined, substantially constant distance at a substantially constant speed, and means whereby said marking means is actuated by said member during a portion of the movement thereof, said last-named means comprising a rotary valve carried by said member, a valve casing having an outlet, a supply of marking fluid connected to said casing, said valve having means for connecting said supply to said outlet for a predetermined interval during the movement of said member.
11. In a rail flaw detector mechanism, means responsive to flaw adapted to generate continuous impulses of varying duration depending upon the size and type of flaw, rail marking means, operating means for said marking means comprising a motor, means whereby said impulses set said motor in operation, means whereby said marking means is actuated by said motor during a predetermined portion of the period during which said motor is in operation, and means for rendering said motor ineffective after a predetermined period, said period being in excess of the longest impulse duration.
12. In a rail flaw detector mechanism, means responsive to flaw adapted to generate continuous impulses of varying duration depending upon the size and type of flaw, rail marking means, operating means for said marking means comprising a movable member, means whereby said impulses move said member through a predetermined, substantially constant distance at a substantially constant speed, means whereby said marking means is actuated by said member, said last-named means including an electric circuit, contacts in said circuit, and means whereby said member actuates said contacts during a predetermined portion of the movement of said member.
